WINDING DEVICE

Ernest R. Marsters, Bedford, Mass., assignor to Electro Devices Inc., Boston, Mass., a corporation of Massachusetts

Application August 6, 1953, Serial No. 372,730

10 Claims. (Cl. 242—4)

This invention relates to machines for winding strand material about an annular core which is closed upon itself and more particularly for winding wire upon a toroidal type core to produce electric coils of the toroidal type.

In machines of this type it is necessary that the strand material or wire to be wound on the core can be stored on a device which may pass through the space or hole enclosed by the core in order that the strand may be properly wound. It is also necessary that some means be provided to maintain tension at some or all times between the wire applied to the core and that being fed or withdrawn from the storage device.

Heretofore many machines have been proposed for accomplishing such purposes with varying degrees of success on cores of large inside diameters but have not been satisfactory for cores with an inside diameter of one eighth of an inch or less, and most such devices require a considerable number of steps in their operation. Some of these steps require taking apart the ring in which the wire is stored and from which it is delivered and their storage capacity is so limited that their store of wire must be very frequently renewed.

This invention has as its principal purpose to provide a toroidal coil winding machine which is of simple construction, inexpensive to manufacture, of large storage capacity and in which the wire can very quickly be wound directly on or in a storage ring or shuttle of very small cross section, the shuttle having a smooth outer surface and no parts to remove when winding on, or feeding out, the wire.

Another object of this invention is a coil winding machine in which the wire is wound round a core under controlled tension by novel means integral with the ring or shuttle and not decreasing the storage capacity of the shuttle.

A further object of the invention is to provide a ring, or shuttle, for winding toroidal coils, in which the storage compartment extends continuously therearound, and is almost as large in cross sectional area as the area of the hole in the core and on which the outside surface of the ring or shuttle has no attachments or projections to decrease the area available for the storage compartment.

To accomplish these objects, the device comprises a split ring or shuttle of substantially tubular cross section with an outside continuous slot through which the wire is wound and stored on the hollow inside. The ring is supported by idler supporting pulleys which engage its outer periphery and there is a drive pulley, preferably carried by a pivoted drive pulley arm. These pulleys are

2

preferably grooved like sheaves and confine the wire in the outer storage compartment inside of the ring.

The ring or shuttle is resilient and is split laterally, which split there is preferably a telescopic joint, and on the inner periphery of the shuttle a wire delivery aperture is positioned, preferably near the joint. The tension of the strand between the core and the aperture, when winding a core, tends to draw the split ends together and telescope the joint thereby contracting the circumference of the ring or shuttle. A predetermined length of the strand sufficient to form one turn around a cross section of the core, is thus delivered under controlled tension.

The principal feature of this device is the elimination of the delivering of a strand from the outside or side of the ring or the storing of a strand as an helical coil in a non continuous circumferential compartment or on a bobbin inside the ring. A continuous strand may be first wound as a spiral with successive overlying circular turns passing through a slot in the unobstructed surface of the outer periphery of a ring whose cross section is substantially tubular and the outside diameter of which can be only a little less than the inside diameter of the core. By forming the inside of the groove or storage compartment in the ring, with a smooth surface and storing the strand as a continuous spiral, the ring can deliver or feed out the wire to the core from the inside of the ring by causing the whole spiral coiled strand to slip around in the groove or storage compartment intermittently as the wire is pulled out at each turn around the core.

20 In winding the wire or strand through the peripheral slot and into the tubular storage compartment of the shuttle, the split, resilient shuttle is in its normal expanded condition. The wire or strand is wound around the shuttle under such tension as to prevent kinks, coils and twists, thereby forming a compact continuous spiral coil but the tension is not sufficient to contract the shuttle to its minimum circumference. Thus the coiled strand is retained under control and in frictional engagement with the inside of the storage compartment until a pull on the strand contracts the shuttle and permits the coiled portion to slip around the compartment.

25 A slack take-up means is provided in the form of friction plates which are preferably two half discs of transparent material facing each other inside the upper half of the hollow portion of the ring, one or both plates being spring pressed together. The terminal tips of the plates which are near the core are a little above it so that the loop of slack wire, pressed between the plates, will be released at said tips just as the strand again becomes taut in the next cycle of rotation.

30 By providing a special downwardly and outwardly extending guide from the opposite terminal tip of one of the friction plates and a pivoted trip finger extending into it, this finger acts as the contact arm of a switch to open and close a shunt circuit to an electric counter to count the turns on the core.

35 In the drawings, Fig. 1 is a side elevation of a preferred embodiment of the invention.

Fig. 2 is a fragmentary similar view but with some of the parts in different positions.

40 Fig. 3 is a front elevation of the device shown in Figs 1 and 2, on a larger scale and in section on line 3—3 of Fig. 1.

45 Fig. 4 is a diagrammatic side elevation in section of the preferred form of ring or shuttle at the commencement of winding a continuous strand in overlying turns

into the storage compartment, or peripheral groove thereof, and with the delivery aperture leading the split, telescopic joint.

Fig. 5 is a view similar to Fig. 4 showing the ring or shuttle, turned through an angle of 180°, showing the coiled strand stored within the peripheral groove, showing the strand delivery aperture trailing the split, telescopic joint and showing the inner terminus of the strand affixed to the core.

Fig. 6 is a view similar to Fig. 4 showing that instead of turning the shuttle through 180° to unwind the shuttle and wind the core it is possible, but not desirable, to unwind without such turning and with the aperture leading the split telescopic joint.

Fig. 7 is a view similar to Fig. 5 showing the preferred position of the shuttle for unwinding with the aperture trailing close behind the split telescopic joint in the path of rotation of the shuttle and showing the strand at the point in its path when it first causes the shuttle to contract, causes the stored coil to slip around in its compartment and causes a predetermined length thereof to be drawn through the aperture.

Fig. 8 is a fragmentary, enlarged, side view in section, of the shuttle illustrating the preferred configuration of the telescopic joint and the preferred substantially tangential direction of the aperture therein.

Fig. 9 is a fragmentary, enlarged, front view in section of the preferred cross sectional shape of the shuttle of the invention, and

Fig. 10 is a diagrammatic view, similar to Figs. 5 and 7 showing the various stages of winding one turn around a cross section of a core with the shuttle of this invention, including the friction plates, although the latter are not illustrated.

A typical embodiment of this invention is shown in Figs. 1 and 2 wherein the core winding apparatus I includes a base 20 above which the winding mechanism and counting mechanism is supported. Also shown is a spool 21, carrying a supply of the wire or strand W to be wound around a core to form a toroidal coil T.

An upstanding bracket 25 is fixed to base 20 and provided with a supporting arm 26, pivoted to bracket 25 at 27, for supporting an electric motor M. Motor M is provided with a drive pulley 28, around which a drive belt 29 is trained, the belt 29 being in turn trained around a larger pulley 30 journaled at the free end 31 of an arm 32. Arm 32, at its opposite end 33, is carried in a slot 35 at the top of an upstanding post 36 fixed to base 20. A knurled set screw 37, forms a pivot for the end 33 of arm 32 and may be tightened in a well known manner to fix the arm 32 at various angles to post 36. As indicated in Fig. 2, motor M and drive pulley 28 function as a weighted tension pulley for drive belt 29 since the weight of the motor urges the motor in a clockwise direction around the pivot 27 of supporting arm 26 and being free to so rotate, maintains the belt under tension when arm 32 is lowered as in Fig. 1, or raised as in Fig. 2. A smaller pulley 40 is also journaled at the free end 31 of arm 32, to revolve with the larger pulley 30 and is preferably of the grooved sheave type to enable it to frictionally engage the outer periphery of the ring or shuttle A and drive the same.

The ring or shuttle A is preferably of one piece of material, such as metal and is annular in shape whereby it is unconnected to, and unsupported at, the centre of rotation thereof. It is provided with a split at 42 enabling it to be slightly distorted to permit its insertion in the hole or space encircled by the closed annular core T which core is to be wound with strand W to form a toroidal coil. In this invention, the ring or shuttle A instead of being supported around its inner periphery as in former winding devices, is supported by at least two idler pulleys, 44 and 45, each being grooved to engage and retain the outer periphery of the ring while permitting the ring to be revolved by drive pulley 40. Preferably idler

pulleys 44 and 45 are each journaled at an opposite end of, and between, a pair of cross bars 47 and 48, each cross bar being supported by a centrally disposed bracket portion such as 49 at a fixed height above base 20.

Supporting mechanism G for holding a closed annular core such as T in various positions of traverse is provided, and preferably includes a carrier member 50, having its lower leg 51 pivotally mounted at 52 to the base 20. An upstanding portion 53 of member 50 is provided with a handle 54 and the upper leg 55 of member 50 constitutes the lower jaw 56 of a clamp H. The upper jaw 57 of clamp H includes a threaded element 58, threadedly engaged in the lower jaw 56 and a guide pin 59 slidably engaged in lower jaw 56 at the rear thereof. Coil springs such as 60 may encircle both pin 59 and element 58 for lifting the upper jaw when the knob 62 of element 58 is turned to unloosen clamp H. A pair of removable jaw plates 63 and 64 may also be provided, each movable with a jaw and both of the desired size to grasp cores of various sizes. As shown in Fig. 1 a core T may be clamped in the clamp H at the correct position for winding and gradually traversed on pivot 52 to another position such as that shown in Fig. 2, while ring A is progressively winding strand W around a cross section of the core.

As best shown in Figs. 4-10, the ring or shuttle A is a split, hollow, annular member, normally self-sustaining in substantially circular form but of resilient material, or otherwise inherently expandable, whereby it may be contracted to slightly less circumferential length and then expanded again to normal circumferential length. It is the essence of this invention that the strand storage means B, the strand delivery aperture C, and the strand tensioning means D are all integral with the one piece ring or shuttle A, whereby the shuttle may be of an especially small cross sectional area for winding cores of minute size such as one eighth inch inside diameter or considerably less.

The strand storage means B of the shuttle A includes an inner peripheral wall 70 spaced from the centre of rotation of the shuttle, unsupported thereon and unconnected thereto for supporting a plurality of overlying turns of the continuous strand W. Storage means B also preferably includes a pair of spaced apart, opposite side walls 71 and 72, extending circumferentially around inner wall 70 and forming a strand receiving groove therewith for retaining the continuous turns of strand W. As best shown in Fig. 9, preferably the inner wall 70 and side walls 71 and 72 are bent into a tube of circular cross section with the free upper edges 73 and 74 of the side walls 71 and 72 spaced apart to form a winding slot 75. A tubular strand storage compartment is thus formed, rather than merely a groove, the compartment extending continuously around shuttle A with one open end 76 thereof facing or overlapping the other open end 77 thereof at the split 42.

The strand delivery aperture C, unlike previous winding machines having a strand wound continuously, entirely around an annular shuttle, is positioned in the inner periphery of the shuttle A, and extends through the inner wall 70 intermediate of the side walls 71 and 72. Preferably the aperture C extends substantially tangentially through the inner peripheral wall 70 of shuttle A, rather than radially thereof and is located proximate the split 42. As best shown in Fig. 8 a strand being delivered through aperture C from the direction of joint J, is thus guided at an obtuse angle rather than an acute angle to thereby prevent binding.

The strand tensioning means D, of the shuttle A functions because of the contractability and expandability of the material of the shuttle, together with the positioning of the aperture relative to the split 42 therein. As shown in Figs. 1 and 4, the free end 7 of the continuous strand W is led from spool 21 through the eye 8 of a rotating traveler 9, thence through a guide eye 10 on a

guide wire 11, thence under a tension clip 12 on arm 32. The end 7, as best shown in Fig. 4, is then passed through slot 75 in the outer periphery of shuttle A, then out of the storage compartment through aperture C in the inner peripheral wall 70 of shuttle A and then is anchored in a transversely extending hole 13 in the shuttle A. Shuttle A is then revolved counterclockwise by motor M until a predetermined length of the strand W has been wound around shuttle A in the tubular storage compartment of storage means B. The strand W is then cut off leaving a terminal end 14, and the shuttle A at this time contains a plurality of overlying turns of the continuous strand W sufficient to wind the core T. The shuttle A is, of course, wound or filled in its normal expanded condition, although preferably it is wound under slight tension sufficient to contract it imperceptibly. Upon completion of the winding, the shuttle then tends to expand slightly and thereby locks the coils of strand W in place in the shuttle A. Prior to winding or filling the shuttle, as above described, the shuttle is expanded or distorted sidewise at split 42, one end thereof such as 76 is passed through the hollow space of the closed annular core and the shuttle is returned to its normal annular shape.

As shown in Fig. 6, without moving the shuttle A after filling the same and after cutting off the end 14 from the spool 21, the end 7 of strand W could be removed from transverse hole 13, attached around a cross section of core T and motor M again started. However, as illustrated, the aperture C would then be leading the split 42 in the counterclockwise path of rotation of the shuttle causing the strand W to bend back upon itself as it wound around core T, thereby possibly binding at aperture C.

It is therefore preferred that after the shuttle A is filled, the arm 32 be raised to free the shuttle from its supporting and driving means, and the shuttle revolved around a vertical axis into the position shown in Figs. 5, 7 and 10. The arm 32 is then lowered and the shuttle A is so positioned that the aperture C trails the split 42, proximate the same, in the path of rotation of the shuttle.

Returning now to the strand tensioning means D of shuttle A, the split 42 is most coil winding machines is formed by shuttle ends which abut one upon the other. Such a construction obviously would not permit contraction of the shuttle. I have discovered that the ends of the shuttle at the split, if shaped to abut must be spaced apart to form a gap whereby upon contraction the gap may close but that such a construction is not desirable since the lack of a bridge across the gap may cause the coiled strands to lack support, bend or become distorted.

It is possible to bridge the gap with a single extension of the inner peripheral wall 70 extending from one open end 76 of shuttle A to overlap the inner peripheral wall 70 of the opposite end 77 and it is possible to provide a pair of oppositely disposed extensions of wall 70, each overlapping the other to bridge the gap. However, as best shown in Fig. 8, I prefer to provide a telescopic joint J at the split 42 in the one piece resilient shuttle A as part of the strand tensioning means D.

An integral substantially tubular extension 80 is provided at one open end of shuttle A, turned down to slidably fit within a substantially tubular recess 81 bored within the opposite end of the shuttle A, there being a shoulder at 82 and a shoulder at 83. Thus without decreasing the area of the storage means B, the shuttle A may contract and expand at split 42 without danger of lack of support for the overlying turns of strand W and without danger of distortion of the shuttle A.

In winding a core T, as indicated in Figs. 5, 7 and 10 the end 7 of strand W is attached around a cross section of the core and the shuttle A is revolved with the aperture C trailing the telescopic joint J. The pull of strand W tangentially through aperture C as the aperture moves along points 1, 2 and 3 in the path of rotation, causes the inner, or underlying, turns of the strand W in storage

means B to tighten, thereby contracting the circumference of the shuttle and telescoping the joint J. The turns the strand W are thus released of their frictional engagement with the inside walls of the storage groove, or compartment, and slip around therein to feed or deliver length of strand through the aperture C.

Upon reaching the point of maximum distance from core T, such as at 4 in Fig. 10, a predetermined length of the strand will have been drawn through the aperture C and the tension on the strand thereupon releases when slack commences to appear in the delivered portion thereof. Release of the strand tension permits the resilient shuttle to again expand, spreading the telescopic joint J and again locking the overlying turns of strand W in frictional engagement with the inside walls of storage means B. As aperture C and joint J continue along the path of rotation of shuttle A, past points 5 and 6 thereof slack increases as indicated in Fig. 10. Upon passing through the core T, the delivered portion of strand W completes its closed path around a cross section of the core and upon the aperture reaching points 1, 2 or 3 in the path of the shuttle, the slack is again eliminated as the turn around the core ceases to be loose. At about point 3, the delivered portion of strand W becomes taut and commences to exert tension on both the previously wound around the core, thereby tightening it, and upon the coiled strand within storage means B, thereby causing the shuttle to again contract and the coiled strand to slip therearound. The exact, predetermined length of the strand W required to complete a new turn around cross section of core T, is then drawn or delivered from aperture C, while joint J is telescoped and the shuttle then again expands at about point 4. The cycle is repeated until all of the strand W in the storage compartment of shuttle A has been wound around core T, the carrier member 50 being moved progressively, or as desired to cause the strand to be wound at the desired place on core T. It should be noted that the free end 14 of strand W, and the coils thereof, cannot escape through slot 75 of shuttle A, while winding a core since they are held in the compartment by drive pulley 40 and idler pulleys 44 and 45.

Preferably slack take-up means E is provided comprising a semi circular plate 90 and a pivotally mounted plate 91, both preferably of transparent material. Each plate 90 or 91 is positioned opposite to the other in the upper half of the hollow space within shuttle A. Plate 90 is immovably fixed above base 20 by any convenient means such as plate 93, pins 94 and plate 95, the latter being fixed to cross bar 48. Plate 91 is hinge pivoted to 95 to a supporting member 96 and member 96 is affixed to a supporting member 97, the latter being hinge pivoted at 98. A coil spring is provided at hinge 98 to continually urge plate 91 against plate 90 with a predetermined pressure exerted over the entire surface of the plate. Preferably the terminal tips 100 and 101 of the adjacent ends of plates 90 and 91, proximate the core T are in a slightly higher plane than the core T and than the opposite terminal tips 106, 107, as shown in Fig. 1. The pressure plates 90 and 91 are thus in the two upper quadrants of the circular path of rotation of the shuttle, when the strand W becomes slack, and tend to retard the loosening in these quadrants as well as to press out any coils or kinks created in the strand. The tips 100 and 101 release the gradually diminishing loop just as the loop is at its smallest extent and just as the aperture C reaches points 1, 2 or 3 on its next cycle of winding.

Counting mechanism F is preferably provided including a contact arm 110 of a micro switch 111, the arm 110 being curved upwardly and outwardly and extending across the path of the delivered portion of strand W between points 3 and 4 on the path of rotation of shuttle A. Micro switch 111 is included in a circuit of well known type, which circuit includes the electric counter 112 and a source of current not shown. Preferably a

outwardly curved ear 115 is provided at the terminal tip 06 of plate 91, whereby the delivered portion of strand V upon riding up and around contact arm 110 is guided back into the space between plates 90 and 91.

Preferably the tension clip 12, under which strand W ravelas as it is led from spool 21 into the shuttle A upon winding or filling the shuttle, includes a knob 120 and a graduated dial 121, whereby the tension on the strand as it passes clip 12 may be set, controlled and adjusted in a well known manner.

The shuttle or ring A may be of any desired circumferential length but I have found it convenient to use a circumferential length of twelve inches when the circumferential length of a single turn around a core is to be about one inch. Thus each time the shuttle revolves, one inch of strand will be withdrawn. With each revolution of the shuttle A, the electric counter will indicate such revolution and if twenty-four turns are desired, the device is stopped when the counter indicates the figure 4. Preferably at least two or three extra turns of strand V are wound into the storage means B of shuttle A than will be needed to wind the core T, to assure that there will be overlying turns thereof toward the end of the unwinding of the shuttle. Thus if it required six feet of strand to make the necessary turns around core T, at least nine feet of strand is stored in storage means B. The extra length of strand is broken off and discarded at the termination of the winding of a core T.

I claim:

1. A winding machine for winding strand material round annular closed cores including clamp means to hold a core, said machine including an annular, resilient, substantially tubular, split shuttle normally expanded to form a closed circle; a continuous outside slot around said shuttle for receiving strand material spirally wound thereon; an inside strand delivery hole in said shuttle to deliver a strand through an annular core; tension means including circumferential contractability and expandability of said shuttle to control tension on the strand between the inside strand delivery hole and a core; a plurality of pulleys supporting said shuttle only on the outside thereof; a drive pulley frictionally engaging the outside of the shuttle, and power means for revolving the drive pulley.

2. An annular, one piece shuttle, for winding toroidal coils, said shuttle comprising an inner peripheral wall of resilient material forming a closed figure capable of circumferential contraction and expansion, said wall being spaced from a center of rotation but unsupported therein, and unconnected thereto for supporting a plurality of overlying turns of a continuous strand; a pair of spaced part, opposite side walls, extending circumferentially round said inner wall and forming a strand receiving groove therewith for retaining the overlying turns of a continuous strand; rotatably mounted sheaves spaced round only the outside of said shuttle, at least one of which is power driven, for engaging and supporting the outer periphery of said circular shuttle and revolving the same about said center of rotation; a freely telescopic joint at a lateral split in said shuttle for retaining the closed and grooved configuration thereof during circumferential expansion and contraction of said shuttle and a strand delivery aperture extending substantially tangentially through said inner peripheral wall, between said side walls, said aperture being positioned proximate said telescopic joint whereby tension on a strand wound continuously around said shuttle and having an end projecting from said aperture tends to contract said shuttle at said joint and temporarily free the turns of said strand from frictional retention by said shuttle.

3. In winding apparatus for winding strand material round a closed annular core, the combination of a split, hollow, annular shuttle formed of one piece of resilient material said shuttle having a normal circumferential length and integral strand storage means coextensive with

the outer periphery thereof for supporting and frictionally retaining the overlying turns of an annular supply of an elongated strand continuously wound around said shuttle when said resilient shuttle is of normal circumferential length; a strand delivery aperture located in the inner periphery of said shuttle through which the inner turns of a strand wound around said shuttle may be withdrawn from under the overlying turns thereof; strand tension control means, including contractability of said resilient shuttle to less than normal circumferential length, for effecting the withdrawal of a predetermined length of said strand with each rotation of said shuttle, while simultaneously exerting controlled tension on the portion of said strand wound on a core during the previous rotation of said shuttle, and shuttle supporting and drive means, engaging only the outer periphery of said shuttle for supporting said shuttle and rotating the same around a fixed center of rotation.

4. A combination as specified in claim 3 wherein said strand tension control means includes a hollow, freely telescopic joint forming part of said strand storage means at the split in said resilient shuttle and the delivery aperture of said shuttle is positioned proximate and in rear of said joint on the path of rotation when unwinding said shuttle.

5. A shuttle for use in a toroidal core winding machine, said shuttle comprising a one piece closed ring of hollow, tubular resilient material normally expanded to a predetermined circumferential length but contractible to a lesser circumferential length and adapted to contain an annular supply of continuous strand wound therearound, a freely telescopic hollow joint at a single lateral split in said ring for maintaining the circumferential continuity thereof during expansion and contraction, a continuous slot extending completely around the outer periphery of said ring, including said joint, for receiving a strand for coiling in said hollow tubular ring and a strand aperture located in the inner peripheral wall of said tubular ring close to said joint for delivering a strand from within said ring, said ring being arranged to resiliently clamp said annular strand supply against rotation relative thereto when expanded but to permit relative rotation of said annular supply when contracted by the pull on the strand exerted through said strand aperture onto the underruns of said annular strand supply.

6. A shuttle as specified in claim 5 wherein the axis of said strand aperture is angled toward said joint to guide said strand at an obtuse angle out of said shuttle during delivery thereof.

7. An annular, split, resilient shuttle for toroidal core winding machines, said shuttle having a continuous external groove adapted to contain an annular strand supply wound therearound and being adapted to resiliently clamp said supply against relative rotation when the shuttle is in normal expanded condition and having an internal strand delivery aperture, said shuttle including a contractable joint at said split and being contractable circumferentially from its normal expanded condition to release said annular strand supply to rotation around said groove thereby permitting withdrawal of a length of strand from said aperture.

8. A shuttle as specified in claim 7 wherein said shuttle is of uniform circular, tubular cross section with an open, unobstructed peripheral winding slot extending continuously around a smooth, outer, peripheral face.

9. A shuttle as specified in claim 7 wherein at least one split end of said shuttle overlaps the other split end with a slideable, contractable fit when said shuttle is in said normal expanded condition.

10. A shuttle for toroidal coil winding machines, said shuttle comprising a ring of resilient material having a continuous annular external groove therearound for containing an annular supply of strand wound in overlapping convolutions and for resiliently clamping said annular supply against circumferential rotation within said groove

when said ring is in normally expanded condition and means for controlling withdrawal of strand from said groove while maintaining predetermined tension on said strand, said means including an internal feed aperture in said ring for permitting withdrawal of strand from beneath said annular supply and a freely telescopic joint at a split in said ring for enabling said ring to contract circumferentially under tension of strand exerted through said internal aperture, thereby unclamping said annular supply and enabling rotation thereof in said groove in the 10 direction of feeding.
